(57) **CLAIM**

We claim the ornamental design for a hand-held tablet, as shown and described.

DESCRIPTION

FIG. 1 is a front view of a hand-held tablet showing our new design;

FIG. 2 is a rear view thereof;

FIG. 3 is a top view thereof;

FIG. 4 is a bottom view thereof; and,

FIG. 5 is a front perspective view thereof.

The broken lines in the drawings represent portions of the hand-held tablet that form no part of the claimed design.
